SPRING FLASK COMPRESS

Bert A. Roelofs, Kalamazoo, Mich.

Application July 13, 1933, Serial No. 680,244

5 Claims. (Cl. 18—33)

The main objects of this invention are:

First, to provide an improved spring compress for dental molds and the like.

Second, to provide a spring flask compress that is simple and economical in its parts and effective and efficient in operation.

Objects relating to details and economies of my invention will appear from the description to follow. The invention is defined and pointed out in the claims.

A structure which is a preferred embodiment of my invention is illustrated in the accompanying drawing, in which:

Fig. 1 is a side elevation of a compress embodying the invention, a second flask being indicated by dotted lines.

Fig. 2 is a fragmentary side elevation partly in vertical section on line 2—2 of Fig. 3.

Fig. 3 is a horizontal section on line 3—3 of Figs. 1 and 2, a flask being indicated by dotted lines.

Fig. 4 is a fragmentary side elevation partly in vertical section of a modification.

Referring to the drawing, 1 is a conventional dental mold or flask operatively associated with the compress 2. The compress or clamp consists of a frame 3 comprising a base 4, integral side uprights 5 extending therefrom, and an integral cross member or support 6 connecting the upper ends of the uprights. The support 6 has a central opening 7 through which is disposed the bolt 8 having a nut 9 and a head 10. The nut engages the top of the support 6, while the head 10 is provided with a radial flange 11 disposed in spaced relation to the support 6. A volute spring 12 of heavy strap steel is disposed around the head 10 between the support 6 and the flange 11 for urging the head 10 downwardly away from the support 6.

The bolt 8 has a longitudinal central bore 13 in which is threaded the set screw 14 for initially engaging the spacing or filler block 15 disposed on the mold 1 or with the top of the upper mold where a plurality of molds are used, the upper mold in this case being indicated by the dotted lines 16 of Fig. 1. A force distributing plate or disk 17 is disposed between the block 15 and the flask 1 when the block 15 is used and between the lower end of the set screw 14 and the top of the upper flask 16 when the block is unnecessary, the position of the force distributing member in the latter case being indicated by the dotted lines 18 of Fig. 1.

In operation, the flask 1, force distributing plate 17, and block 15 are arranged on the base

4 of the frame 3 directly under the set screw 14 which is thereupon turned to engage the lower end thereof with the top of the block 15, a screw driver being used for this purpose. The nut 9 is then backed off or unscrewed so that the full force of the compressing spring 12 is released and transmitted through the set screw 14 to the mold or molds assembled thereunder. After the molding process, the nut 9 is tightened so as to retract the compression spring 12 and the set screw 14 is unscrewed so as to release the block 15 and/or the plate 17, whereupon the dental flask or flasks may be removed from the compress. In the molding or vulcanizing process, the compression spring 12 urges the flask sections tightly, but resiliently, together. The set screw 14 serves the two-fold purpose of (1) holding the flasks in place prior to releasing the spring 12 and (2) transmitting the force of the spring 12 to the flasks in the compress. The spring 12 is preferably designed to have enough tension to properly close one or more flasks.

Referring to Fig. 4, there is illustrated a modification wherein the cross member or support 6 of the frame is provided with an opening 7 in which is disposed the bolt 19 having a head 20 engaging the top of the support and a nut or lower end member 21, the latter being provided with a radial flange 22 which constitutes a lower end thrust member for the volute compression spring 12 and a force distributing plate for engaging the top flask 16 when a plurality thereof are assembled in the compress. In operation, the flasks are assembled in the frame below the flange 22 and the head 20 is then turned so as to release the spring 12 to clamp the flask through the nut 21. After the vulcanizing process, the head 20 is tightened so as to elevate the nut 21, thereby compressing the spring 12 and releasing the flasks. In this modification, the parts are few and relatively simple and the individual parts are readily removable and replaceable.

The frames are preferably adapted to receive at least two large flasks, and when fewer or smaller flasks are used, the intervening space is filled with the spacing block 15 or its equivalent. I prefer to use a solid metal member for this purpose. A particularly desirable feature of my invention resides in the fact that the potential force of the compression spring 12 is utilized quickly and conveniently by merely releasing the spring after the flasks have been inserted in the compress.

The set screw 14 of the modification illustrated in Figs. 1 to 3, inclusive, provides means whereby

the full force of the compression spring may be applied to the flask or flasks directly and without using the spring to expend its force by filling the intervening space which is taken care of by the 5 set screw 14. Also, the arrangement is such that the force of the spring is expended on the bolt, thereby leaving the set screw free to be turned to release or engage the flasks with a relatively slight manual effort.

10 I have illustrated and described my improvements in embodiments which I have found very practical. I have not attempted to illustrate or describe other embodiments or adaptations, as it is believed this disclosure will enable those skilled 15 in the art to embody or adapt my improvements as may be desired.

Having thus described my invention, what I claim as new and desire to secure by Letters Patent is:

20 1. A compress for dental molds, comprising a frame comprising a base, integral uprights extending therefrom, and an integral horizontal cross member connecting said uprights, said cross member having a central opening, a bolt disposed through said opening and having one end member engaging the top thereof and the other end member disposed under said cross member and in spaced relation thereto, said last named end member having a radial flange, and a volute 25 spring disposed around said bolt between said flange and said cross member and urging these parts away from each other, said bolt having a longitudinal central bore, and a set screw threaded in said bore for engaging the top of the mold.

30 2. A compress or clamp for dental flasks, comprising a frame adapted to receive a flask and having a top piece with an opening therein, a volute coiled spring formed of flat stock disposed below said top piece with its outer coil engaging

the same, a spring support member engaging the inner coil of the spring and having a threaded stem disposed through said opening in said top piece, a nut threaded on said stem whereby the spring may be collapsed, and a screw threaded into said support for adjustment independently thereof for initially engaging the top of the flask before the pressure of the spring is released by unscrewing said nut.

3. A compress for dental molds, provided with 10 a support having an opening, a bolt disposed through said opening and having a nut engaging said support, a volute spring disposed around said bolt between said support and the head of said bolt and urging said head away from said support, 15 the nut limiting the movement of said bolt, said bolt having a longitudinal central bore, and a set screw threaded in said bore for initially engaging the top of the mold before the pressure of the spring is released by unscrewing said nut.

4. A compress for dental molds, provided with a support having an opening, a bolt disposed through said opening and having an upper end member engaging said support and a lower end member spaced therefrom, a volute compression 20 spring disposed around said bolt between said support and said lower end member, said bolt having a longitudinal central bore, and a set screw threaded in said bore for engaging the top of the mold.

5. A compress for dental molds, provided with a support having an opening, a bolt disposed through said opening and having a nut engaging said support, a compression spring disposed between said support and the head of said bolt, said bolt having a longitudinal central bore, and a set screw 25 threaded in said bore for engaging the top of the mold.
